UNITED STATES PATENT OFFICE.

JOHN MALIK, OF PITTSBURGH, PENNSYLVANIA.

RAILWAY-TRACK CONSTRUCTION.

1,353,771.

Specification of Letters Patent. Patented Sept. 21, 1920.

Application filed January 19, 1920. Serial No. 352,244.

To all whom it may concern:

Be it known that I, JOHN MALIK, a citizen of Poland, residing at Pittsburgh, in the county of Allegheny and State of Pennsylvania, have invented certain new and useful Improvements in Railway-Track Construction, of which the following is a specification.

This invention relates to certain new and useful improvements in railway track constructions and is particularly designed to permit the employment of track rails of sectional formation, the sections of the track having interfitting and detachable connection with each other whereby, one of said sections of each rail is adapted for receiving most of the wear and capable of being renewed.

Another object of the invention is to provide a track construction of the above type wherein the rail sections are co-operatively constructed for reception upon a novel form of ties so as to present a highly efficient and durable railway.

With the above general objects in view and others that will become apparent as the nature of the invention is better understood, the same consists in the novel form, combination and arrangement of parts herein-after more fully described, shown in the accompanying drawings and claimed.

In the drawings, wherein like reference characters indicate corresponding parts throughout the several views,

Figure 1 is a transverse sectional view of a track construction embodying the present invention,

Fig. 2 is a view thereof partially in plan and partially broken away,

Fig. 3 is a perspective view of one of the ties shown in Figs. 1 and 2,

Fig. 4 is a transverse sectional view illustrating a modified form of the invention,

Fig. 5 is a similar view illustrating a further modification of the invention,

Fig. 6 is a perspective view of the wear receiving rail section of Figs. 1 and 2,

Fig. 7 is a similar view of the other section of the rail, and

Fig. 8 is a fragmentary perspective view illustrating the application of the invention to switch or crossing rails.

Referring more in detail to the several views, the present invention contemplates the provision of a rail composed of two longitudinal sections 5 and 6 which are dis-

posed side by side as shown in Fig. 1. The lower portion of the section 6 is outwardly flanged, as at 7 and is provided with the usual ball or tread member 8 at its upper edge. One side face of the rail section 6 is cut away as at 9 so as to form a rabbet within which the upper portion of the rail section 5 is seated, and the rail section 6 has a longitudinally extending rib 10 upon its inner face within said rabbet. The rail section 5 is formed with a complementary groove longitudinally of the inner side face thereof as at 11 so as to snugly receive the rib 10 whereby the two rail sections 5 and 6 interfit. The sections 5 and 6 may be retained operatively related by any suitable means, said means being herein illustrated as comprising a plurality of stud bolts or screws 12 which are passed through suitable perforations 13 provided in the web of the section 5 and which are threaded into sockets 14 provided in the sections 6 at suitable intervals. The sections 5 and 6 are thus effectively joined so as to provide a rail which is substantially as durable as a one piece rail, and the section 6 may be renewed from time to time as found desirable by reason of breakage or undue wearing thereof. Obviously, the section 6 will be subjected to much greater wear than section 5 as said section 6 is provided with the entire rail head or ball 8 upon which the wheels of the railing stock bear and run. The section 5 is also outwardly flanged at its lower edge as at 15 so that the two flanges 7 and 15 jointly form substantially the usual flange base such as is commonly found upon one piece rail constructions now in use.

The structure is made somewhat more durable by the provision of a novel form of tie 16 best shown in Fig. 3. This tie is of the usual form with the exception that the same is provided with seats 17 at its opposite ends constituted by undercut transverse grooves which are of such depth as to accommodate the flanges 7 and 15. The grooves forming the seats 17 being undercut, the sides 18 of said seats converge upwardly toward each other and contact the chamfered edges 19 and 20 respectively of the flanges 7 and 15 whereby the rail sections 5 and 6 are effectively held in their seats 17. The seats 17 are thus of substantially dovetailed formation as is also the base of the rail formed by the flanges 7 and 15. It is to be understood that the sections 5 and 6 are

slid longitudinally into the seats 17 to their proper positions.

Each seat 17 of the tie 16 is provided with a central longitudinally extending upstanding rib 21 which is preferably of inverted V-shape in cross section, and the rail sections 5 and 6 are both outwardly chamfered as at 22 at the lower portions of their meeting faces so as to provide a groove of such form as to snugly receive the rib 21. This form of seat in combination with the particular rail used produces a very durable track construction.

In Fig. 4, the construction shown is substantially the same as that of the embodiment above described with respect to Figs. 1 to 3 inclusive and 6 and 7, with the exception that the inner rail section 5' is formed also with a head 8' and acts as a guard rail 20 in the usual and well known manner.

In Fig. 5 a construction is shown whereby removal of the rail sections may be had without sliding the same longitudinally out of their seats 17. This is accomplished by 25 inclining the contacting faces 23 and 24 of the rail sections 5 and 6 upwardly and leaving a slight space as at 25 between the free edge of the flange 7 and the adjacent side wall 18 of the seat 17 whereby, when the 30 screws 12 are removed, the section 5 may be tilted away from the section 6 and bodily removed by an upward pull.

In Fig. 8, the construction of the rail is substantially the same as shown in Fig. 1 35 with the exception that the rail section 6 is provided with an enlarged and laterally extended head 26 which overlies and rests upon the upper edge of the rail section 5 and is provided with flange receiving grooves 27 40 and 28 which cross each other as at 29 so as to form the usual switch or crossing track as will be apparent.

In view of the foregoing description, it is believed that the construction and operation 45 of the present invention as well as the ad-

vantages thereof will be readily understood and appreciated by those skilled in the art.

It is to be understood that minor changes may be made in the form, combination and arrangement of parts without departing 50 from the spirit and scope of the invention.

What I claim as new is:

1. In a railway track construction, a rail composed of a pair of longitudinal sections positioned side by side and each having outwardly directed base flanges, one of said rail sections being provided at its upper edge with a ball and being rabbeted at one side for the reception of the upper portion of the other section, one of said sections being 60 provided with a longitudinal rib upon its inner face, the other section having a complementary longitudinal groove receiving said rib, means to fasten the rail sections together, said rail sections being chamfered 65 at the lower portions of their inner faces to provide a substantially inverted V-shaped groove, a railroad tie having a transverse seat formed therein for the reception of said base flanges of the rail sections, and an upstanding substantially inverted V-shaped rib longitudinally and centrally disposed in said seat and received within the groove of the rail. 70

2. The combination with a railroad tie 75 having a transverse seat formed therein by an undercut groove, of a rail resting in said seat and having dove-tailed engagement with the latter, said rail comprising a pair of longitudinal separable sections, one of 80 said sections being provided with a rail head and being adapted to be renewed, the base of said rail being provided with a longitudinal inverted V-shaped groove, and a central upstanding rib formed on the tie 85 centrally of the seat thereof for snug reception within the groove of the rail.

In testimony whereof I affix my signature.

JOHN MALIK.
